UNITED STATES PATENT OFFICE.

NEGIB BECHARA HANI, OF PARIS, FRANCE.

ROLLER-BEARING.

1,165,594.

Specification of Letters Patent. Patented Dec. 28, 1915.

Application filed June 24, 1914. Serial No. 848,975.

To all whom it may concern:

Be it known that I, NEGIB B. HANI, a subject of the Ottoman Empire, and residing in Paris, France, have invented certain new and useful Improvements in Roller-Bearings, of which the following is a specification.

In the different attempts which have been made to employ roller bearings for heavy loads difficulty has been encountered resulting from lateral shocks due to the force of projection when vehicles moving at a high speed undergo a change of direction. In order to obviate this disadvantage the present invention provides an arrangement permitting a roller bearing to withstand such lateral shocks without adversely affecting its parallel movement, the lateral shocks according to this arrangement being absorbed by the casing of the bearing itself, the friction upon the end abutment of the bearing resulting from these shocks being at the same time considerably reduced.

According to the system constituting the subject matter of the invention a steel ring is arranged transversely to the journal and adjacent to the rollers, this ring being secured in the roller cage by a bearing sleeve which closes the bearing casing and is secured by a number of bolts to this casing. A number of thin steel annular disks independent of one another are arranged between the steel ring above referred to and other rings transmitting lateral stresses, these annular disks constituting the friction surface of considerable area thereby diminishing the risk of seizing, while at the same time the construction is capable of resisting lateral shocks without injury to any parts of the bearing, since the arrangements for rotary movement are quite independent of the arrangements for withstanding end thrust.

The bearing system of the invention above described which is particularly suitable for railway services will be clearly understood from the following description relating to the accompanying drawing which illustrates in longitudinal section a form of bearing suitable for axles of railway vehicles, and especially for the driving axles of such vehicles.

The axle journal A is for a considerable portion of its length surrounded by a bearing sleeve B, a number of rollers C being arranged around this sleeve and carried in a casing D divided into three parts, the casing

D being located in the interior of the axle box E. The rollers C are preferably reduced in cross section as indicated at a in order to accommodate corresponding rings b secured to the interior of the axle box E. The construction so far described, does not however form part of the present invention.

The axle box E is provided at its outer end with an enlargement forming an abutment c for a steel ring F through which the journal passes freely but which is secured on its seat formed by the enlargement c by means of a securing member G formed integral with a cap H constituting a cover for the axle box, the cap H being secured to the axle box E by means of bolts.

A number of thin steel disks d, d¹, are arranged on either side of the ring F, these disks being quite free and out of engagement with the journal A and the axle box E. The disks d, d¹, are capable of sliding relative to one another if, for any reason, such for instance as an engagement between them resulting from a lateral shock, the disks are pressed against one another.

At one side one of the sets of steel disks d is interposed between the steel ring F and another ring I which is freely mounted in the axle box E and bears against the end of the bearing sleeve B surrounding the journal A. The other set of steel disks d¹, is arranged on the outer side of the bearing between the ring F and the ring J which is freely mounted in the bearing member G and is supported by a ring K mounted upon the extremity of the journal A.

In the event of lateral shocks upon the bearing, one or other of the rings I or J approaches the stationary ring F and either the disks d or d¹ are pressed one against the other according to the direction of the lateral shock experienced by the bearing.

The individual disks of one or other of the sets d or d¹ which are freely mounted in their respective places in the bearing can, if the stress to which they are subjected is sufficiently great, be displaced relative to one another without seizing, the friction surfaces being greatly increased owing to the number of the disks, thus having the result of preventing any injury to the bearing or rotating surfaces due to seizing.

The arrangement above described, the function of which is to resist lateral shocks, can evidently be applied to both ends of each

bearing in which case disks would be provided at each end of the rollers instead of only at one end as shown in the drawing.

The lubrication of the bearing is insured by causing the moving parts to be immersed in an oil bath during operation, the space M for oil being formed in the axle box E, the bearing surface of the journal being arranged above the level of the oil in this space which is kept full of oil.

A suitable number of leather rings, c are provided located in grooves in the axle box E for the purpose of preventing leakage.

Claims:

- 15 1. A bearing for journals of car wheels comprising a bearing part, a sleeve adapted to fit on the journal and bear upon a shoulder at the inner end of the journal, rollers adapted to lie between said bearing part and said sleeve, a plate transverse of the journal adapted to be secured to said bearing part to sustain the end thrust of the journal, said plate being axially outward of the journal, and a plurality of loose independently movable plates between said transverse plate and said sleeve, adapted to receive the end thrust transmitted through said sleeve.
- 20 2. A bearing for journals of car wheels comprising a bearing part, a sleeve adapted to fit on the journal and bear upon a shoulder at the inner end of the journal, rollers adapted to lie between said bearing part and said sleeve, a plate transverse of the journal

adapted to be secured to said bearing part to sustain the end thrust of the journal, said plate being axially outward of the journal, and a plurality of loose independently movable plates on opposite sides of said transverse plate between said transverse plate and said sleeve and said transverse plate 40 and a shoulder on the outer end of said journal.

3. A bearing for journals of car wheels comprising a bearing part, a sleeve adapted to fit on the journal and bear upon a shoulder at the inner end of the journal, rollers adapted to lie between said bearing part and said sleeve, a plate transverse of the journal adapted to be secured to said bearing part to sustain the end thrust of the journal, said 50 plate being axially outward of the journal, a loose rotatable plate between said transverse plate and said sleeve, and a plurality of relatively thin independently movable plates between said transverse plate and said 55 rotatable plate, said loose plates being adapted to receive the end-thrust transmitted through said sleeve.

In witness whereof, I have hereunto signed my name in the presence of two subscribing witnesses.

NEGIB BECHARA HANI.
